UNITED STATES PATENT OFFICE.

HIRAM G. SEDGWICK, OF MILL VALLEY, CALIFORNIA, ASSIGNOR TO THE NATIONAL SAFETY APPLIANCE COMPANY, A CORPORATION OF CALIFORNIA.

AUTOMATIC TRAIN-STOP.

1,082,825.

Specification of Letters Patent.

Patented Dec. 30, 1913.

Application filed December 24, 1903, Serial No. 469,093. Renewed April 25, 1913. Serial No. 763,665.

To all whom it may concern:

Be it known that I, HIRAM G. SEDGWICK, a citizen of the United States of America, and a resident of Mill Valley, county of Marin, State of California, have invented certain new and useful Improvements in Automatic Train-Stops, of which the following is a full and clear specification, reference being had to the accompanying drawings, in 10 which—

Figure 1 is a view partly in section and partly in side elevation showing my invention applied to a locomotive; and, Fig. 2 is a detail vertical section of one form of vent-15 valve mechanism.

My invention has relation to that type of automatic train-stops covered by my pending application, Serial No. 459,358, filed October 24, 1908.

20 When the locomotive is running tandem, that is, behind one or more preceding locomotives in the same train, it is the rule for the rear locomotives to cut out their brake-controlling means completely, so that the 25 leading locomotive will have sole control of the brake mechanism of the train.

The object of the present invention is to provide means whereby when the engineer cuts out his brake mechanism he will by the 30 same act break or open the operating circuit controlled by the roadbed devices whereby this circuit will be rendered inoperative even though the locomotive pass over roadbed devices set to danger, the device being especially adapted for the normally-closed circuit mechanism shown and claimed in my 35 aforesaid application.

Referring to the drawings annexed by reference characters the letter *a* designates the 40 train-pipe of the usual air-brake mechanism; *b* the usual storage reservoir; *c* the usual pipe leading from said reservoir to the engineer's valve *d* and thence to the train-pipe, by which the supply of air to the train-pipe 45 is kept at normal pressure; *e* is a pipe connecting the train-pipe to the engineer's valve through which pipe *e* the train-pipe is vented, the air escaping through a port *f* in the valve in the usual manner; *g* is a double cut-off in 50 pipes *e* and *c*, at a point below the valve *d*, by means of which said valve *d* may be cut off from the brake apparatus and rendered incapable of affecting the brake mechanism. All the above parts are constructed in the 55 usual manner.

The cut-off valve *g* is used to cut out the controller-valve when the locomotive is attached to a train behind one or more preceding locomotives, in which case it is the rule for locomotives to cut out their brake-controlling means completely so that the leading locomotive will have complete control of the brake mechanism.

I prefer connecting the vent-valve to the train-pipe by a pipe *i* through the medium 60 of the vent-pipe *e*, at a point between the cut-off valve *g* and controlling valve *d*, so that when the engineer's valve is cut out the vent-valve mechanism will also be cut out but with my present invention the pipe *i* 65 may be connected directly to the train-pipe *a* if it be desired to do so.

The vent-valve mechanism shown consists of a main valve *h* gravitatingly sliding in a vertical cylinder *j* and normally closing the 70 vent *k* in the side of said cylinder. The vent-pipe *i* enters this cylinder at a point below the vent *k* and communicates with a port *l* in the side of the main valve. To insure the valve *h* against sticking in its cylinder I 75 prefer employing a spring *m* normally forcing said valve downwardly. From the side of the cylinder *j* at a point below the normal position of the valve *h* is a port *n* which leads into the cylinder *o* of a pilot-valve *p* 80 which valve is normally pressed upwardly by a spring *q* to normally close port *n* and also normally close an inlet pipe *c* connecting said cylinder *o* to the pipe *e* leading from the storage reservoir. The valve *p* is provided with a circumferential port *r* and with a stem *s* extending out through the upper 85 head of its cylinder.

Mounted above the pilot-valve is a pair of 90 magnets *t* which are included in a normally-closed circuit *u* and are kept normally energized. These normally energized magnets normally hold up a drop-weight *v* directly over the stem *s* of the pilot-valve, the opposite branches of this normally-closed circuit 95 are connected to the respective branches *w* of the normally-open operating circuit connected to the current collectors which in this instance are the axle and a brush *x*. At a point adjacent to the cut-off valve *g* one of 100 the branches *w* is broken and provided with contact terminals *y* which are adapted to be connected or bridged by means of a contact *z* carried by the cut-off valve *g* when the valve is opened.

- It will be observed that when the normally-closed circuit *u* is weakened by the closing of the circuit *w* by the roadbed devices the magnets *t* will be sufficiently de-
 5 energized to drop the weight *v*. The dropping of the weight *v* on the stem *s* forces down the pilot-valve until its port *r* registers with the inlet port *c'* and the port *n*, where-
 10 upon air from the reservoir *b* will be let in under the main valve *h* to lift the same far enough to bring its port *l* into communication with the vent port *k*, thus venting the train-pipe and applying the brakes. When the cut-off valve *g* is operated to cut out the
 15 controlling-valve *d* the bridging piece *z* will be disconnected from one of the contact-plates *y* and thus render partial circuit *w* inoperative even though its terminals make connection with stopping devices set to dan-
 20 ger. This is advantageous in that otherwise where a locomotive is running behind another its vent-valve would be operated without the engineer being aware of the fact, which would be dangerous in that after the
 25 locomotive is disconnected from that train the automatic stopping devices might be in an inoperative condition without the engineer being made aware of that fact.
- It is obvious that this improvement may
 30 be employed in connection with other forms of vent-valve mechanism.
- It is obvious also that it will be desirable to employ in connection with this automatic cut-out device the means claimed in my
 35 aforesaid application for protecting the wires *w* by normally-closed loops from the normally-closed circuit *u*.
- Having thus fully described my invention, what I claim as new, and desire to secure by
 40 Letters Patent, is:
1. In an automatic train-stop, a vent-valve connected to the train-pipe, electro-magnetic devices for opening the same embodying a normally-closed circuit, a normally-open op-
- erating circuit connected to said closed cir- 45
 50 cuit, this normally-open circuit having a pair of separated contact-plates in one branch, a movable bridge-piece for connecting these contact-plates, this bridge-piece being shifted to break the circuit by the closing of the cut-off valve in the brake mechanism.
2. In an automatic train-stop, a train-pipe system embodying a cut-off valve for rendering the controller-valve inoperative, a 55 vent-valve and electro-magnetic devices for opening the same embodying a normally-closed circuit, an operating circuit connected to the normally-closed circuit and having its terminals connected to current-collecting or 60 contact devices and having a break in one of its branches, and means operated by the aforesaid cut-off valve to close and open said brake, for the purpose set forth.
3. In an automatic train stop, a train pipe 65 system embodying a cut-off valve for rendering the controller valve inoperative, a vent valve and electro-magnetic devices for controlling the same, and means operated by said cut-off valve to render the electro-mag- 70 netic devices inoperative.
4. In an automatic train stop, an air brake system embodying a cut off valve for rendering the engineer's valve inoperative, an emergency vent valve for applying the 75 brakes and automatic means for opening said vent valve, and devices operated by the closing of said cut off valve to render the vent valve operating means inoperative, for the purpose set forth.

In testimony whereof I hereunto affix my signature in the presence of two witnesses this 10th day of December, 1908.

HIRAM G. SEDGWICK.
